SUGAR DISPENSER

Harry C. Gessler, Brooklyn, N. Y.

Application November 28, 1933, Serial No. 700,041

3 Claims. (Cl. 221—61)

This invention relates to devices such as dispensers for granulated or finely divided materials, and has particular reference to sugar dispensers.

One object of the invention is to provide a device of the character described having an improved means for universally controlling a valve for closing and fully opening a port, and an improved screen mounting for effectively breaking up lumps of pulverulent material such as sugar, and whereby the screen is maintained in unclogged condition; and the invention may include either or both of these features in combination.

Another object of the invention is to furnish a device of the nature set forth, having few and simple parts, and which is inexpensive in construction, durable, reliable, and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary vertical sectional view of a device embodying the invention.

Fig. 2 is a top plan view of a separate screen and valve unit embodying the invention.

Fig. 3 is a fragmentary sectional view of the device of Fig. 1, in tilted discharging position.

Fig. 4 is a view in elevation showing in detail the connection between the valve and screen.

Fig. 5 is a similar view showing a modified connection.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a device embodying the invention, and illustratively shown as incorporated in a sugar spill. The latter may have any container which may include the usual glass container 11, and a metallic cover 12 suitably or threadedly connected

thereto as at 13. The cover may be variously shaped and desirably has a conoidal wall 14, and a large port 15 in axial alignment therewith and with the container. The wall 14 may be flared into the port as shown at 16.

For closing the port, a closure may be provided which seats along the outside or rim of the port, and may be variously constructed, as by being of inverted conical shape, whereby the closure 17 referred to constitutes a valve which may be self guiding into accurate seating engagement with the port.

In order to permit substantially the entire area of the port to be available for discharge of material, the valve 17 may be mounted as by a thin wire or rod 18 which passes through the port 15. This wire is connected at one end 19 to the apex of the conical valve, preferably in fixed alignment therewith, and at its other end to a stop or anchorage on or within the cover 12, to prevent removal of the valve.

Preferably the anchorage connection of the rod 18 is movable so as to afford universal movement of the valve 17 so that the latter may be readily gravitationally opened, as by its own weight, when the device 10 is tilted in any direction.

The stop or anchorage may be connected to the other end of the rod 18, as at 20, and consists generally of a weight 21 for actuating the valve and for maintaining the same in fully opened or closed positions according to the position of the dispenser 10, but regardless of its operation as a weight, it functions as a stop. It is noted that the member 21 has a relatively large diameter and may be relatively flat, but a particularly desirable characteristic is that the member has openings at a distance from its edge or periphery. As a result of these features, more particularly described hereinafter, the port 15 is not obstructed, since the contact or stop engagement of the member 21 with the cover 12 is at a point or along a line on the wall 14 remote from the port 15, and the pulverulent material having free access to the port within the boundaries of said point or line through the openings mentioned.

Particularly described, the member 21 may include a suitable screen 22, which may be of usual woven wire form. The area of the screen may be many times the area of the port. Desirably, the screen may have an annular rim or channel element 23 extending peripherally around the screen to reinforce the same, and to enclose the ends of the wires thereof which would otherwise project and interfere with the cleaning of the device 10. This is important, because the screen is separate

of and disconnected with respect to the cover 12, so that the edge of the screen is always free, except for the rim 23.

Due to the conoidal form of the cover, the screen member is maintained remote from the port 15, and the entire screen area is operatively available.

The screen member may be connected to the rod 18 in any suitable manner, preferably centrally, as by means of a limited pivotal connection as at 24, or a fixed detachable connection as at 25, which may be considered as affording detachability broadly in the screen valve unit to facilitate cleaning of the dispenser. The former means of connection may consist of a loop 26 of the rod 18 engaged snugly frictionally around a wire of the screen 22, and the latter may include a fitted or threaded connection as at 27 between the rod 18 and a disc or bushing 28 having a peripheral groove 29 so as to be snapped into an opening of the screen or otherwise engaged therewith, so that cross wires of the screen are reliably received in said groove.

According to this invention the screen operates as a weight or stop or both for the closure valve, and in the open position of the latter the port 15 is fully open on the valve side and also on the screen side thereof.

Another feature of the invention is that the device includes a movable screen arranged to be jarred by impact, particularly when the device is tilted and the screen member or rim thereof strikes the wall 14. The screen may be used independently of the valve action.

The device is in all respects universal, the screen member accommodatively engaging the wall 14, in any tilted position of the device. Such engagement may occur with either connection 24 or 25 but may be particularly facilitated by the former, in which case the valve may have sufficient weight for a substantially balancing relation with the screen member to maintain the parts in desired relation in the tilted position. The engagement at 24 may be limited as to angular range of movement by adjacent wires of the screen, or the latter may be in such proximity to the cover as to be stopped by the same. It will be obvious that the screen may be at a higher elevation than as shown in Fig. 1.

In use, the device 10 is tilted or inverted to discharge its contents, which are compelled to flow through the screen, as the same seats on the conical wall of the cover, and the flow is rapid and full through the port 15. When the device is returned to upright position, the valve automatically seats shut, closing the port against any entrance of dust and the like, while the screen drops, assuring complete release of material. Any material left adhering to the screen may be removed by impact of the screen when the device is again tilted. As the tilting occurs, the lower portion of the screen seats on the wall 14, and finally the entire screen swings into seating position, so that the screen operates effectively.

It will be appreciated that various changes and modifications may be made in the device as shown in the drawing, and that the same is submitted in an illustrative and not in a limiting sense, the

scope of the invention being defined in the following claims.

I claim:

1. A sugar dispenser comprising in combination, a container, a conoidal cover connected to the container, said cover having a central discharge port, a valve outside of the cover adapted to seat on the port, a relatively flat screen for said port within the cover, and a substantially rigid link relatively rigidly centrally interconnecting the valve and the screen so as to provide a unit having a common axis, the screen being smaller than the inside of the cover so that said unit is freely movable relative to the cover, said link being substantially smaller in diameter than said port with the link swingably engaging the wall of the port to control the positions of said unit, said unit being otherwise independent of the cover with the valve and screen being automatically swingable into cooperation with said port on tilting the container through different angles of relatively large size to establish a wide range of operation for the sugar dispenser.

2. A sugar dispenser comprising in combination, a container, a conoidal cover connected to the container, said cover having a central discharge port, a valve outside of the cover adapted to seat on the port, a relatively flat screen for said port within the cover, said screen consisting of wire mesh, an externally grooved nut fitted into a relatively central opening of the screen with the wires of the latter engaging in said groove, a substantially rigid link centrally relatively rigidly connected to the valve and removably threadedly engaged with said nut, whereby the valve and screen provide a unit with the valve and screen alternately movable into operative position relative to said port, and so that the screen has a relatively large range of contact with the wall of the cover, in different tilted positions of the container.

3. A sugar dispenser including a container having a cover provided with a central top port, a valve for the port, a screen within the container, said valve being of inverted conoidal shape so as to seat on the outside of the rim of the port, and a rigid vertical wire link rigidly axially connected to the valve at the lower end thereof and being rigidly connected to the screen to constitute the valve and a generally horizontally extending screen a relatively inflexible gravitationally actuated unit, said link being substantially smaller in area than the port so as not to obstruct the same, said valve being movable outward and away from the port to open the same, said valve and screen being spaced to permit the movement of the valve with the screen serving as a stop by abutment against the cover and the screen preventing clogging of the port, and said link maintaining said valve and screen in operative alignment and permitting a limited angular movement of said unit upon tilting and inverting the dispenser, with the conoidal face of the valve serving as a guide into said port for returning the unit to initial vertical position upon righting the dispenser.

HARRY C. GESSLER.
